Primary Examiner — Angela J Lee*Assistant Examiner* — Shawn T Gingrich(74) *Attorney, Agent, or Firm* — Leydig, Voit & Mayer, Ltd.(57) **CLAIM**

The ornamental design for an electrical connection plug, as shown and described.

DESCRIPTION

FIG. 1 is a front-right-top perspective view of an electrical connection plug showing an embodiment of our new design; FIG. 2 is a right-side view thereof; FIG. 3 is a front view thereof; FIG. 4 is a top view thereof; FIG. 5 is a rear view thereof; FIG. 6 is a bottom view thereof; and, FIG. 7 is a left-side view thereof.

The broken lines in the drawings illustrate portions of the electrical connector plug that form no part of the claimed design.
